CLAIM

The ornamental design for a first aid kit, as shown and described.

DESCRIPTION

FIG. 1 is a perspective view of my new design, showing a first aid kit;

FIG. 2 is another perspective view thereof;

FIG. 3 is another perspective view thereof, shown in an alternate position;

FIG. 4 is a front elevation view of the first aid kit shown in FIG. 1;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged partial view of a part enclosed 10 in FIG. 1.

The dashed broken lines shown in the figures illustrate portions that form no part of the claimed design.

The broken lines shown in FIGS. 1 and 10 illustrate the boundary of a detail enlargement area that form no part of the claimed design.

1 Claim, 10 Drawing Sheets
